UNITED STATES PATENT OFFICE

BERNHARDT PARKER, OF NEW YORK, N. Y.

GARBAGE UTILIZATION AND DISPOSAL PLANT

Application filed February 18, 1929. Serial No. 340,713.

My invention relates to garbage systems and refers more particularly to a garbage utilization and disposal system wherein the garbage is utilized and disposed of to the best 5 advantage.

One object of my invention is to provide a means for drying and heating garbage and delivering it in its dried state to the combustion chamber of a furnace.

10 Another object of my invention is to provide a means for removing the volatile products from garbage and directing the same into suitable apparatus wherein the valuable byproducts may be conserved.

15 A further object of my invention is to provide a simple, efficient device for utilizing the byproducts liberated during the treatment of the garbage.

A still further object of my invention is 20 to provide an apparatus that is adapted to separate the valuable volatile elements that are a part of garbage and reduce them to valuable commercial byproducts and at the same time utilizing the other parts for producing power.

Another valuable feature of my invention 25 consists in the arrangement and construction of the apparatus whereby there are no offensive odors or dangerous gases liberated that are associated with the same.

It is well known in the art that garbage disposal and incinerator plants have been used but none contemplate the conservation 30 of the byproducts therein, at the same time utilizing the combustible elements for power purposes and none of these have the same organization of particular elements for producing these results.

I attain these results preferably by the 35 means illustrated in the accompanying drawings, wherein similar parts are referred to by like numerals throughout the several views, in which:—

40 Figure 1 is a partial longitudinal view in section of the apparatus.

Figure 2 is a section taken on lines 2—2 of Figure 1.

Figure 3 is a section taken on lines 3—3 of Figure 1.

Figure 4 is a section taken on lines 4—4 of 50 Figure 1.

The apparatus consists of a substantially air tight retort 1 provided with annular rings 2 and 3 on each end, each ring co-operating with the rollers 4, 5, 6 and 7 which are supported in the supports 8 and 9 and this retort may be revolved by means of the motor 10, carrying a sprocket 11, connected by the chain 12 to the sprocket 13, suitably located on the retort 1. 55

The bearing supports 8 are supported upon the foundation 14 which has an extension at 15 upon which is mounted the supports 16, 17, 18 and 19 holding the enclosing casing 20 through which the retort 1 passes and in which it freely revolves, the collars 21 and 22 provided for sealing the space 23 between the casing and the retort. 60

The casing is extended at 24 providing a combustion chamber 25 for gas or other fuel 70 which may be introduced therein through the pipes 26 and 27 and the heat passes up the passages 28 and 29 past the dampers 30 and 31, provided with adjusting means 32 and 33, into the space 23 surrounding the 75 retort and thence out through the stack 34, as indicated in Figures 1 and 3.

The foundation also carries a fixed material feeder comprised of a tube 35 supported by the supports 36 and projecting into the end 80 of the retort at 37 where it may be sealed in any suitable manner.

This tube carries a suitably shaped hopper 38 which projects beyond the floor 39, so that the garbage wagon or the like 40 may discharge garbage, as shown by the dotted lines 41 into said hopper and this floor is provided with a stop 42 for said wagon. 85

The tube 35 has a piston 43 formed with an apron 44 for sealing the opening through 90

which garbage is fed to the tube and the piston rod 45 extends into a steam, air or water cylinder 46 supported by the supports 56 and 57 having a piston 47 that may be actuated by means of the steam chest 48, the valve 49, valve rod 50 and lever 51 extending above the floor 39 and pivoted at 52 therein.

Steam, air or water may be fed to the cylinder 46 by means of the pipe 53 provided with a valve 54 whose stem or handle 55 extends above the floor 39.

The opposite end of the cylinder 1 projects into a casing 58 provided with an outlet 59 which may carry the volatile products of combustion to any suitable remote point where they may be utilized and this casing is provided with a sealing means 60.

In the bottom of this casing is a feed wheel 61 provided with a pulley 62 connected by a belt or chain 63 to a motor pulley or the like 64 of the motor 65.

The furnace 66, with its front, side, rear walls, roof and floor, has a combustion chamber 67, an arch 68, water tubes 69, drum 70, ash hopper 71, baffles 72 and 73, bridge wall 74, ash dumping doors 75 with an operating handle 76, an outlet 77 provided with a damper 78 and a draft may be induced through this furnace as indicated by the arrows therein by means of the fan 79 with the pulley 80 driven by the belt 81 connected to the pulley 82 of the motor 83, the air being supplied in the usual way through suitable openings such as 92.

Dried material is fed to the combustion chamber 67 of the furnace 66 by means of the chute 84, connected to the casing 58 to a suitable chain conveyor 85 which is provided with a pulley 86, driven by a belt 87, connected to the pulley 64 of the motor 65.

The fan 79 and motor 83 may be supported by any suitable support such as 88 and there may be an extension of the furnace foundation at 89 so that ashes may be removed through the doors 75 in any suitable way to a conveyance in the space 90 and the chain conveyor 85 may be provided with a scraper and guide 91 adapted to remove and direct burnt ashes into the ash pit 71.

Having thus illustrated and described the preferred embodiment of my invention, I do not wish to limit myself to the exact construction or arrangement of parts shown, since it is evident that modifications may be made therein without departing from the spirit of the invention or scope of the claim.

I claim:—

A garbage utilization system, comprised of a foundation supporting a furnace, provided with an endless chain grate, a revolvable, substantially constantly closed retort with a feeding means connected to the inlet end thereof, said retort supported on rollers adjacent the ends and provided with means carrying away volatile gases and having an enclosure be-

tween said rollers with a variably controlled independent heating means at one end at the bottom and an outlet on the opposite end in the top and a revolvable feeder at the outlet end of said retort feeding materials to the endless chain grate in said furnace.

Signed at New York in the county of New York and State of New York this 15th day of February, 1929.
